TOY DIVER FIGURE

Henry Hirsch and Benjamin L. Hirsch, Toledo, Ohio, assignors to Kellogg Company, Battle Creek, Mich., a corporation of Delaware

Application June 6, 1955, Serial No. 36,378

Term of patent 14 years

(Cl. D34—4)

Fig. I

Fig. II

Fig. I is a perspective view taken from the left front of a toy diver figure showing our new design.

Fig. II is a perspective view thereof taken from the right rear.

We claim:

The ornamental design for a toy diver figure, as shown.
